UNITED STATES PATENT OFFICE.

WILLIAM R. RASMUSSEN, OF LOS ANGELES, CALIFORNIA.

FINGER-GUARD.

1,337,957.

Specification of Letters Patent. Patented Apr. 20, 1920.

Application filed October 14, 1918. Serial No. 258,085.

To all whom it may concern:

Be it known that I, WILLIAM R. RASMUSSEN, a citizen of the United States, and a resident of Los Angeles, in the county of 5 Los Angeles and State of California, have invented certain new and useful Improvements in Finger-Guards, of which the following is a specification.

This invention relates to a finger guard 10 particularly designed for use by chefs, butchers, and pantrymen in restaurants or hotels, the object of the invention being to provide a guard for the index finger or thumb of the user which will prevent him 15 from cutting this finger or the thumb, when slicing or cutting edibles.

More specifically, the object of the invention is to provide a finger guard, which is formed of a blank of sheet metal, being bent 20 to form a finger or thumb tip receiving socket having an apron extending upwardly from the socket, the upper edge of which is corrugated or notched to prevent a roughened edge to receive the blade of a knife, 25 and prevent the same from slipping off the guard and consequently cutting the user's hand.

Other objects of the invention will appear 30 in the following detailed description, taken in connection with the accompanying drawing, forming a part of this specification, and in which drawing:

Figure 1 is a perspective view of the finger, and showing the same applied.

Fig. 2 is a side elevation of the guard 35 showing the same mounted upon the tip of the index finger of the user.

Fig. 3 is a front elevation of the device.

Fig. 4 is a horizontal section through the 40 socket portion of the guard.

Referring more particularly to the drawing, 1 generically indicates the guard which is formed of sheet metal, and may be nickel or otherwise finished to please the esthetic 45 sense. The guard 1 comprises the socket portion 2, which is formed by bending the lateral tab 3, to fit about the tip of the index finger or thumb of the user and the lower end of the socket 2 is inclined to permit 50 the tip of the finger indicated at A to

project beyond the guard. The upper portion of the guard 1 forms an apron 4 which is slightly curved and when mounted upon the user's finger projects upwardly above the first joint or knuckle of the finger or thumb as clearly shown in Figs. 1 and 2 of the drawing, forming a protection for the finger of the user in case the knife is brought down over this finger. The upper edge of the apron 4 is serrated, forming notches 5 which will receive the knife blade and prevent its slipping off the upper edge of the apron and consequently cutting the user's hand.

The edges of the apron 4 flare outwardly 65 as they extend upwardly from the socket 2, forming a relatively wide guarding head at the upper end of the apron.

It will be noted by reference to Fig. 4 that the edges of the lateral tabs 3 engage, and these tabs are rolled or bent to form the socket, thus inclosing all of the tip of the finger or thumb with the exception of the extreme end thereof and by allowing the extreme end or ball of the finger tip to project out of the guard, the free use of this portion of the finger or thumb is permitted, in gripping objects to be cut.

Changes in details may be made without departing from the spirit of this invention, but;

I claim:

1. A finger guard comprising a finger receiving socket and an upwardly extending flared apron formed on one end of the 85 socket, the flared free end of the apron having a plurality of inwardly extending knife receiving V-shaped notches formed therein to prevent the slipping of a knife off of said flared end.

2. A finger guard comprising a finger receiving socket and a flared upwardly extending apron formed on the upper edge of the socket, the upper flared end of the apron having a straight free edge, provided with 95 a plurality of equi-distantly spaced inwardly extending V-shaped notches, said notches forming means for preventing a knife from slipping off of said straight upper edge.

WILLIAM R. RASMUSSEN.
